UNITED STATES PATENT OFFICE.

JOHN SWENSSON, OF NEW YORK, N. Y.

FURNITURE-POLISHER.

SPECIFICATION forming part of Letters Patent No. 250,297, dated November 29, 1881.

Application filed June 25, 1881. (No model.)

To all whom it may concern:

Be it known that I, JOHN SWENSSON, of the city, county, and State of New York, have invented a new and useful Improvement in Furniture-Polishers, of which the following is a specification.

The invention relates to improved means for applying to pianos and other furniture the superior gloss known as "French polish."

10 The operation of French polishing has heretofore been performed by means of a piece of cloth wrapped around a piece of cotton, the latter being soaked or dampened with the polishing-liquid (generally a solution of shellac in 15 alcohol) and acting as a feed-reservoir, from which the liquid is gradually squeezed through the cloth by pressure with the fingers of the operator as he rubs the thus formed pad upon the surface of the furniture operated upon.

20 This mode is tedious, requiring much care and skill for obtaining an even polish, and presents extra difficulties in polishing in the junction of two surfaces meeting at an angle, the sharp groove or inner corner between such 25 surfaces being almost inaccessible to the pad.

My present invention has for its object to overcome these difficulties; and it consists in a self-feeding angular polisher, constructed as hereinafter described and claimed.

30 In the accompanying drawings, Figure 1 represents a longitudinal vertical section of my improved furniture-polisher. Fig. 2 is a cross-section of the same, taken on the line $y-y$ of Fig. 1. Fig. 3 is an end view of the same. 35 Fig. 4 is an inside view of the same, the cover and feed-plate being removed. Fig. 5 is a plan view of the feed-plate, seen from the under side.

Similar letters of reference indicate corresponding parts.

40 The polisher consists mainly of a flat-bottomed, square, or angular box, A, whose sides form right or acute angles with the working surface or under side of the bottom, so as to adapt it to be moved along in and in contact with the sharp inner angle between—for instance, a vertically-projecting portion and a horizontal surface of a piece of furniture. One 45 end of the box A may be rounded off to similarly adapt it for contact in the angle between a plain and a curved surface. The bottom of the box may be made convex when it

is desired to specially adapt it for polishing concave surfaces.

The cover B, which is screwed or otherwise fastened to the box A, has a supply-opening 55 closable by a plug, b, through which the box is charged with the polishing-liquid. The bottom is provided with rows of downward-flaring perforations a, through which the liquid 60 flows down to and gradually percolates through an absorbing cloth pad, C, covering the entire under side of the bottom. The upper or inner surface of the bottom is covered by a feed-plate, D, conforming in shape to that of the bottom, so as to fully close all the perforations 65 when desired. The liquid is admitted to the perforations a by means of transverse grooves or channels d cut in the face or under side of the feed-plate D, when said plate is moved into 70 such position that the said grooves partly or wholly uncover the said perforations.

To shut off or to regulate the flow of the liquid, it is only necessary to provide means for keeping the feed-plate D tight upon the bottom of the box A and for sliding it in a direction at right angles to the grooves d. For this purpose the feed-plate is provided in about its center line with two vertically-bored and threaded hubs, in which fit eye-screws E. A 75 rod, F, having its bearings in holes through opposite ends of the box A, is inserted through the eyes of the said screws E at about right angles to the direction of the channels d, and the inner end of the rod F is threaded at f to 80 work in threads formed in the inner screw-eye, e. The rod F is held in its bearings by being provided with a circumferential groove, f', into which fits the correspondingly-shaped edge of a small plate, H, fastened to outside of 85 the end of the box by a screw, h. The outer end of the rod F is bent, or otherwise provided with a handle, G, for turning it. By turning the handle G to the right (if the thread f be right-handed) until the plate D assumes about the 90 position in Fig. 1 it is evident that the flow of the polishing-liquid will be shut off from the perforations a, and by turning the handle G to the left until the grooves d partly or wholly uncover the perforations a the liquid will be 95 admitted in adjusted quantities to less or more moisten the cloth pad C.

To tighten the plate D upon the bottom of the box A, it is only necessary to remove the

plate H and the rod F from the box, then unscrew the eye-screws E one or more half-turns in their hubs, so as to increase the distance between the eyes of the screws E and the face 5 of the feed-plate D, and finally replace the rod F and plate H in the position of Fig. 1. When in use the constructed polisher is held in one hand and rubbed with the cloth pad C in contact upon the surface to be polished, the feed-
10 plate D being first adjusted to admit the proper amount of liquid to the pad.

Having thus described my invention, what I claim as new, and desire to secure by Letters Patent, is—

15 1. In a furniture-polisher, the combination of the box or reservoir A, having rows of perforations a in its bottom, with the sliding feed-plate D, having grooves or channels d in its under side, substantially as and for the purpose set forth.
20

2. The combination of the feed-plate D, having channels d on its under side, and one or more threaded and guiding uprights, E, with the box A, having perforated bottom, and with the rod and feed-screw F f, held in bearings 25 in the walls of the said box A, substantially as and for the purpose set forth.

3. The combination, with the rod F and the feed-plate D, arranged to operate as described, the eye-screws E, threaded in hubs upon the 30 said feed-plate, and fitted with their eyes to slide upon the said rod for the purpose of adjusting the tightness of the feed-plate D, substantially as specified.

JOHN SWENSSON.
